DESIGN FOR A LAMP

Albert Pfaltz, Flushing, N. Y.

Application September 4, 1947, Serial No. 141,210

Term of patent 14 years

(Cl. D48—20)

To all whom it may concern:

Be it known that I, Albert Pfaltz, a citizen of the United States and a resident of Flushing, county of Queens, city and State of New York, have invented a new, original, and ornamental Design for a Lamp, of which the following is a specification, reference being had to the accompanying drawing, forming part thereof, in which the figure is a perspective view of a lamp, showing my new design.

I claim:

The ornamental design for a lamp, substantially as shown.

ALBERT PFALTZ.
